(57) **CLAIM**

I claim the ornamental design for a disk for securing a beverage container, as shown and described.

DESCRIPTION

FIG. 1 is a top perspective view of a new design for a disk for securing a beverage container;

FIG. 2 is front view thereof, the rear view being a mirror image;

FIG. 3 is right side view thereof, the left side view being a mirror image;

FIG. 4 is a top view thereof; and,

FIG. 5 is a bottom view thereof.

The stippling shown in FIGS. 1-3 and 5 depicts a contrast in appearance.
